UNITED STATES PATENT OFFICE.

LOUIS C. TINSLEY, OF NEW YORK, N. Y.

TYPOGRAPHICAL MACHINE.

1,406,107.

Specification of Letters Patent. Patented Feb. 7, 1922.

Application filed March 17, 1921. Serial No. 453,112.

To all whom it may concern:

Be it known that I, LOUIS C. TINSLEY, a citizen of the United States, and a resident of the city of New York, borough of the Bronx, in the county of Bronx and State of New York, have invented a new and Improved Typographical Machine, of which the following is a full, clear, and exact description.

10 This invention relates to improvements in typographical machines, objects of the invention being to provide improved means for compressing a line of matrices, and measuring the length of such compressed line of matrices in the assembler elevator of the machine, and also indicate the length of the space to be filled.

20 My invention is particularly adapted for use in the setting of tabular matter, and can be so arranged as to be used in connection with columns of any desired width.

25 With these and other objects in view, the invention consists in certain novel features of construction, and combinations and arrangements of parts, as will be more fully hereinafter described and pointed out in the claims.

In the accompanying drawings—

30 Figure 1 is a fragmentary view in elevation illustrating my improvements in connection with an ordinary type of typographical machine, only such portions of the machine being illustrated as is necessary to indicate the location and operation of my invention.

35 Figure 2 is a view in vertical section on the line 2—2 of Figure 1.

Figure 3 is a fragmentary view similar to Figure 1, showing the parts in a different position.

40 Figure 3^a is a fragmentary view in section on the line 3^a—3^a of Figure 3.

Figure 4 is an enlarged view in horizontal section on the line 4—4 of Figure 3.

45 Figure 5 is a view in transverse section on the line 5—5 of Figure 4.

Figure 6 is a perspective view of the bracket 22.

50 Figure 7 is a view in transverse section through the assembler slide.

Figure 8 is a perspective view of one of the scale strips 14.

1 represents a typographical machine pro-

vided with the ordinary assembler elevator 2, guide plate 3, chute block 4, belt drive 55 pulley 5, star wheel 6, and assembler slide 7. 2 represents the assembler elevator into which the matrices 8 are fed, and moved or compressed by the star wheel 6, forming a line of matrices against the ordinary assembler slide finger 9.

The parts above described are common in the art, and need not be described in detail, except as they are hereinafter modified to accommodate my invention.

65 The assembler slide 7 is provided at its lower edge with a longitudinal series of ratchet teeth 10, which are preferably cut into the slide, as indicated clearly in Figure 7. Above these teeth 10, the slide 7 is made 70 with a longitudinal groove 11, in the upper portion of which a scale strip 12 is secured by means of screws 13, and operates to clamp also in the groove 11 scale strips 14, length of scale strips 14 being of the width 75 of the column to be set.

A pointer 15 is fixed to the plate 16 of the machine, and registers with the scale strip 12 and also with the scale strips 14.

80 The ratchet teeth 10 are cut one-half em lengths, so that two of these teeth constitute an em. The scale on the strip 12 is in ems and fractions thereof, and the scales on the strips 14 are also in ems and fractions thereof, but the scales on the strips 14 are 85 reverse to the scale on the strip 12, for a purpose which will hereinafter appear.

85 The chute block 4 is provided with a bore 35^a to provide rotary mounting for a tubular arbor 35, the latter internally screw threaded, as shown at 36, and meshing with the threads of a screw threaded rod 17. This rod 17 has a longitudinal groove or keyway 18 for the reception of a key 19, the latter secured to the face of the block 4 by means 90 of a screw 20, so as to hold the rod 17 against turning movement. A compression head 21 is integral with the forward end of the rod 17 to move against the line of matrices, as will more fully hereinafter appear, to compress the line.

100 A bracket 22 is secured to the plate 16 of the machine, and is made with an integral arm 23 having an opening 38 therein constituting a bearing for one end of the arbor 105 35, and said arbor adjacent the arm 23 is

shaped to form a drum 24, around which the intermediate portion of a cord or cable 25 is wound. A disk 26 is fixed to the arbor 35, and is provided on its outer face with a scale indicating points and fractions thereof, and a pointer 27 is made integral with the end of the arm 31 and registers with the scale on the disk.

One end of the cord or cable 25 is passed around a pulley 37 on bracket 22, and is secured to a spring 28, which exerts a normal pull thereon, tending to hold the disk in normal position and the head 21 retracted, as will more fully hereinafter appear.

15 A pawl 29 is pivotally connected to perforated ears 30 on the lower end of bracket 22, and is made with a plurality of teeth adapted to engage the teeth 10 to lock the assembler slide against forward movement when the pawl is pressed against said teeth. This pawl 29 is held in normal spaced relation from the teeth 10 by means of a coiled spring 34 exerting pressure against the pawl. This pawl is provided with an 25 arm 31 pivotally connected to the pawl, as shown at 32, and at its intermediate portion connected to the cord or cable 25 so that the pull of the spring 28 not only operates to maintain the disk 26 at normal position, but also exerts a pull on the arm 31 to maintain the pawl 29 out of engagement with the teeth 10.

The assembler elevator 2, above referred to, is provided with a scale 33, such as is 35 commonly employed to indicate the length of the line of matrices set, but, as these matrices are loosely set, it does not accurately measure the line when the matrices are compressed, and it is the purpose of my invention, not only to compress the line and indicate the measurement of the line set, but also give the minus measurement; that is, the space to fill the line to the width of column desired.

45 The operation of my improvements is as follows: Assuming the matrices 8 shown in the assembler elevator 2 to constitute the matter set for the line, the operator presses downwardly upon the arm 31, which immediately presses the pawl 29 into locked engagement with the teeth 10 to hold the assembler slide against forward movement.

In practice, in order to perfect the engagement of teeth on pawl 29 with teeth 10, 55 the head 21 will move assembler slide 7 the required distance by its pressure against the last assembled matrix 8.

A continued downward movement of the arm 31 exerts a pull on the cord or cable 60 25 to turn the arbor 35 by reason of the contact with this cable, which is wound around the drum 24 constituting a portion of the arbor. This turning movement of the arbor, by reason of its screw threaded 65 engagement with the rod 17, will cause the

longitudinal movement of the rod to press the head 21 against the last assembled matrix 8 in the line, and compress the line of matrices. As the arbor 35 is revolved, it will cause the disk 26 to turn with the same, and, 70 when the line is fully compressed, a glance at the scale on the disk will show, as it registers with the pointer 27, a fraction of an em. This fraction must be subtracted from the number on scale 12, or added to 75 the number on scale 14, which registers with the pointer 15, so that, in the present instance, it will be noted that the line set measures eight ems (minus) on scale 12; and two ems (plus) on scale 14 is indicated 80 as the space to fill the line to the desired point.

In practice, the strips 14 are of a length corresponding to the width of the columns or lines of matrices to be set, and can be 85 readily changed, in accordance with the work to be done.

It will be noted that, by providing the numerals of the strips 12 and 14 in reverse order, both indicating in ems and fractions 90 thereof, the numerals on one of these scales will indicate the length of the line of compressed matrices, and the numerals on the other scale the space to be filled to complete the line, and, in order to give an absolutely accurate measurement, the scale on the disk 26 will provide the fraction of an em, in a point or fraction thereof, of said measurement, which must be added to one of said scales and subtracted from the other 100 to give the results desired.

After the measurement is observed, the operator releases the arm 31, and the spring 28 will return the arm and the other parts to their normal positions, as indicated in 105 Figure 3, so that the head 21 will be out of the way of the matrices falling into the assembler elevator.

It will, therefore, be noted that, with my improvements, I not only accurately measure 110 the line of matrices set, when said line is compressed, but the device also indicates the exact space to be filled to complete the line.

Various changes may be made in the general form and arrangement of the parts described without departing from the invention, and hence I do not limit myself to the precise details set forth, but consider myself at liberty to make such changes and alterations as fairly fall within the spirit 120 and scope of the appended claims.

I claim:

1. In a typographical machine, the combination with an assembler slide, and a finger on the slide, of means for holding the 125 assembler slide against forward movement, means for compressing the line of matrices, and means for measuring the line of matrices while the slide is so held.

2. In a typographical machine, the com- 130

bination with an assembler slide, and a finger on the slide, of means for holding the assembler slide against forward movement, means for compressing the line of 5 matrices against the finger, and means for measuring the line of matrices while the slide is so held.

3. In a typographical machine, the combination with an assembler slide having a 10 fixed finger thereon, and means for assembling a line of matrices against the finger, of a member movable against the last assembled matrix to compress the line, a rotary device imparting longitudinal movement 15 to said member, a disk on the rotary device having a scale thereon, a flexible member wound around the rotary device, a spring exerting a pull on one end of the flexible member, a pawl adapted to lock the 20 assembler slide against forward movement, and an arm connected to the other end of said flexible device and controlling the movement of the flexible device and the pawl.

25 4. In a typographical machine, the combination with an assembler slide having a fixed finger thereon, and means for assembling a line of matrices against the finger, of a member movable against the 30 last assembled matrix to compress the line, a rotary device imparting longitudinal movement to said member, a disk on the rotary device having a scale thereon, a flexible member wound around the rotary device, a 35 spring exerting a pull on one end of the flexible member, a pawl adapted to lock the assembler slide against forward movement, and an arm connected to the other end of said flexible device and controlling 40 the movement of the flexible device and the pawl, said assembler slide having a series of ratchet teeth thereon of half em lengths with which said pawl is adapted to engage and lock the slide against forward movement.

45 5. In a typographical machine, the combination with an assembler slide having a fixed finger thereon, and means for assembling a line of matrices against the finger, of a member movable against the 50 last assembled matrix to compress the line, a rotary device imparting longitudinal movement to said member, a disk on the rotary device having a scale thereon, a flexible member wound around the rotary device, a spring exerting a pull on one end of the flexible member, a pawl adapted to lock the assembler slide against forward movement, an arm connected to the other end 55 of said flexible device and controlling the movement of the flexible device and the pawl, said assembler slide having a series of ratchet teeth thereon of half em lengths with which said pawl is adapted to engage 60 and lock the slide against forward movement.

ment, a fixed pointer, a scale strip on the slide registering with the pointer and indicating the length of the line of matrices set up, and other scale strips on the slide having their series of numerals in reverse 70 order to those of the first-mentioned scale and also registering with said pointer.

6. In a typographical machine, the combination with an assembler slide having a fixed finger thereon, and means for assembling a line of matrices against the finger, of a member movable against the last assembled matrix to compress the line, a rotary device imparting longitudinal movement 75 to said member, a disk on the rotary device having a scale thereon, a flexible member wound around the rotary device, a spring exerting a pull on one end of the flexible member, a pawl adapted to lock the assembler slide against forward movement, 80 an arm connected to the other end of said flexible device and controlling the movement of the flexible device and the pawl, said assembler slide having a series of ratchet teeth 85 thereon of half em lengths with which said pawl is adapted to engage and lock the slide against forward movement, said assembler slide having a groove therein, a scale strip secured in said groove, removable scale strips clamped in the groove by the first- 90 mentioned strip, said scale strips having numerals in reverse order, the last-mentioned strips being of a length equal to the width of the column to be set, and a single pointer registering with both of said scale strips. 95

7. In a typographical machine, the combination with an assembler slide having a fixed finger thereon, and means for assembling matrices in a line, of a sleeve having rotary mounting in the machine and in 105 alignment with the assembler slide, a rod located in the sleeve and having screw threaded engagement with the sleeve, means preventing rotary movement of the rod, a head on the rod adapted to engage the last 110 assembled matrix to compress the line of matrices between said head and the finger of the slide, a drum on said sleeve, a flexible device wound around the drum, a spring connected to one end of the flexible device and 115 exerting a pull thereon, a pawl adapted to engage the slide and hold the same against movement, an arm of the pawl connected to the other end of said flexible device, a scale disk on the sleeve, and a pointer registering 120 with the scale disk.

8. In a typographical machine, the combination with an assembler slide, and a finger on the slide, of means for holding the assembler slide against forward movement, 125 and means operable simultaneously with the other of said means for indicating the space to be filled to complete the line.

9. In a typographical machine, the combination with an assembler slide, and a fin- 130

ger on the slide, of means for holding the assembler slide against forward movement, line compressing means engaging the last assembled matrix and exerting pressure toward the finger to compress the line, and means for measuring said line while so held and compressed.

10. In a typographical machine, the combination with an assembler slide, and a finger on the slide, of means for holding the assembler slide against forward movement, line compressing means engaging the last assembled matrix and exerting pressure toward the finger to compress the line, means for measuring said line while so held and compressed, and means indicating the space to be filled to complete the line.

11. In a typographical machine, the combination with an assembler slide having a fixed finger thereon, and means for assembling a line of matrices against the finger, of a member movable against the last assembled matrix to compress the line, a rotary device imparting longitudinal movement to said member, a disk on the rotary device having a scale thereon, a flexible member wound around the rotary device, a spring exerting a pull on one end of the flexible member, a pawl adapted to lock the assembler slide against forward movement, an arm connected to the other end of said flexible device and controlling the movement of the flexible device and the pawl, a chute block, and said line compressing means mounted in and supported by the chute block.

12. In a typographical machine, the combination with an assembler slide having a fixed finger thereon, and means for assembling a line of matrices against the finger, of a member movable against the last assembled matrix to compress the line, a rotary device imparting longitudinal movement to said member, a disk on the rotary device having a scale thereon, a flexible member wound around the rotary device, a spring exerting a pull on one end of the flexible member, a pawl adapted to lock the assembler slide against forward movement, an arm connected to the other end of said flexible device and controlling the movement of the flexible device and the pawl, said assembler slide having a series of ratchet teeth thereon of half em lengths with which said pawl is adapted to engage and lock the slide against forward movement, a chute block, and said line compressing means mounted in and supported by the chute block.

13. In a typographical machine, the combination with an assembler slide having a fixed finger thereon, and means for assembling a line of matrices against the finger, of a member movable against the last assembled matrix to compress the line, a rotary

device imparting longitudinal movement to said member, a disk on the rotary device having a scale thereon, a flexible member wound around the rotary device, a spring exerting a pull on one end of the flexible member, a pawl adapted to lock the assembler slide against forward movement, an arm connected to the other end of said flexible device and controlling the movement of the flexible device and the pawl, said assembler slide having a series of ratchet teeth thereon of half em lengths with which said pawl is adapted to engage and lock the slide against forward movement, a fixed pointer, a scale strip on the slide registering with the pointer and indicating the length of the line of matrices set up, other scale strips on the slide having their series of numerals in reverse order to those of the first-mentioned scale and also registering with said pointer, a chute block, and said line compressing means mounted in and supported by the chute block.

14. In a typographical machine, the combination with an assembler slide having a fixed finger thereon, and means for assembling a line of matrices against the finger, of a member movable against the last assembled matrix to compress the line, a rotary device imparting longitudinal movement to said member, a disk on the rotary device having a scale thereon, a flexible member wound around the rotary device, a spring exerting a pull on one end of the flexible member, a pawl adapted to lock the assembler slide against forward movement, an arm connected to the other end of said flexible device and controlling the movement of the flexible device and the pawl, said assembler slide having a series of ratchet teeth thereon of half em lengths with which said pawl is adapted to engage and lock the slide against forward movement, said assembler slide having a groove therein, a scale strip secured in said groove, removable scale strips clamped in the groove by the first-mentioned strip, said scale strips having numerals in reverse order, the last-mentioned strips being of a length equal to the width of the column to be set, a single pointer registering with both of said scale strips, a chute block, and said line compressing means mounted in and supported by the chute block.

15. In a typographical machine, the combination with an assembler slide having a fixed finger thereon, and means for assembling matrices in a line, of a sleeve having rotary mounting in the machine and in alignment with the assembler slide, a rod located in the sleeve and having screw threaded engagement with the sleeve, means preventing rotary movement of the rod, a head on the rod adapted to engage the last

assembled matrix to compress the line of matrices between said head and the finger of the slide, a drum on said sleeve, a flexible device wound around the drum, a spring connected to one end of the flexible device and exerting a pull thereon, a pawl adapted to engage the slide and hold the same against

forward movement, an arm on the pawl connected to the other end of said flexible device, a scale disk on the sleeve, a pointer 10 registering with the scale disk, a chute block, and said line compressing means mounted in and supported by the chute block.

LOUIS C. TINSLEY.
